UNITED STATES PATENT OFFICE.

HENRY J. COOPER, OF INDIANAPOLIS, INDIANA

RAILWAY RAIL AND TIE PLATE.

Application filed June 22, 1927. Serial No. 200,578.

In laying railway tracks allowance must be made for variations in the length of the rails caused by expansion and contraction of the metal from which they are made due to changes in temperature. This is commonly cared for by elongating the bolt-holes of the fish-plates at the rail-joints so the joints can open when the rails contract in cold weather and close when they expand in hot weather.

10 But the rails often move more in one direction than the other and one rail more than the other, causing unevenness in rail level on the one hand and a carrying of the ties to positions oblique to the rails and a narrowing of the track on the other.

So far as I am aware no practical means for anchoring or holding the rails at their mid lengths, but leaving them free to slide on the ties in both directions from their middle anchorage has been put in practice, and the object of this invention is so to hold the rails at their middles leaving their remaining portions extending from the middles to each end, free, that the expansion and contraction of the rails may be distributed and equalized, and the track damage from rail expansion and contraction largely obviated.

I accomplish the above and other objects which will hereafter appear by the means illustrated in the accompanying drawing, in which—

Fig. 1, is a view in side elevation of a track embodying my invention, showing one full rail and the ends of adjoining rails, making joints therewith;

Fig. 2, is a cross section on a larger scale on the line 5—5 of Figs. 1 and 4;

Fig. 3 is an underside plan view of the full rail shown in Fig. 1;

Fig. 4, is a fragment in side elevation of the middle portion of the rail and track shown in Fig. 1, but on a larger scale;

Fig. 5, is a top perspective view of my preferred form of tie-plate; and

Fig. 6, is an end view of a modified form of tie-plate showing corrugations on the side next to the tie as well as on the rail contacting side.

Like characters of reference indicate like parts in the several views of the drawing.

The ties 1 are preferably formed out of wood, of usual size and are laid on a roadbed 2, in the usual manner. The rails 3 are of any usual and suitable construction, as a whole, here shown with a base 4, web 5, and head 6. Such rails are usually about 30

feet long and in carrying out my invention I form the bottom of the rail for approximately six feet in length at the middle of the rail, with transverse indentures or corrugations 7.

The rails thus corrugated are laid as to their uncorrugated bottom faces, upon tie-plates 8 of usual construction; and the corrugated portions 7 are laid upon tie plates 9, the top surfaces of which are provided with corrugations 10, corresponding in size and shape with the corrugations 7 of the rail. The corrugations of the plates interlock with the corrugations of the rail and hold them from movement relative to each other. The corrugation 7 on the rail should not project below the line of the bottom face of the rail in order that the rail may, when necessary, be used with the usual flat-faced tie-plate.

The tie-plates all preferably have holes through which spikes 11 pass and the spikes are driven into the wooden ties below. The spikes 11 are of usual construction with heads 12 that overlap the respective flanges 80 of base 4, as shown in Fig. 4, thereby holding the corrugations of the rail in those of the corrugated tie-plates so the rail cannot slide on said tie-plates; but where the smooth rail-base contacts the face of a smooth tie-plate, the rail there will be free to slide on the smooth plate. By driving the spikes through holes in the corrugated tie-plates and thence into the ties the plates are immovably fastened to the ties, and by the interlock of the corrugations of the rails with the corrugations of the tie plates, the rails are immovably locked to the tie-plates and also to the ties, at those portions of the rails where corrugations occur thereon. Such corrugated places being only at the middles of the rails it follows that the middles of the rails are locked against movement while the remaining rail portions or parts toward each end are free to slide over the smooth faced tie plates contacting them in obedience to the laws of expansion and contraction. The resulting changes in rail lengths will thus be equalized,—that is, distributed equally in two opposite directions.

In the modification shown in Fig. 6, the tie plate is corrugated on both sides, the bottom corrugations by contacting the wooden ties and entering the wood more or less deeply, assist the spikes in locking the plates to the ties.

While I have shown corrugations of a

well defined and simple pattern in the rails and tie plates, these may be varied in pattern, shape, size and depth according to conditions or desire without departing from the spirit of my invention and the plates may be secured to the ties with any desired number of spikes.

I claim:

1. A railway rail having a flanged base and a series of indents over a minor portion of the bottom of the flanged base located approximately midway of the length of the rail in combination with ties arranged at intervals along and transversely of the rail length, tie-plates between the rail and ties some of which contact the indented surface of the rail and have detents corresponding with and engaging some of the indents of the rail, and means for securing the rail and plates to the ties.
2. A railway rail having a flanged base and a series of indents over a minor portion of the bottom of the flanged base located approximately midway of the length of the rail in combination with ties arranged at intervals along and transversely of the rail length, tie-plates between the rail and ties

some of which contact the indentured surface of the rail and have detents corresponding with and engaging some of the indents of the rail, spike holes through the plates, and spikes having heads, said spikes passing through the holes in the tie-plates and driven into the ties and impinging the flanged base between the spike head and tie plate.

3. A railway rail having a flanged base and a series of transverse corrugations extending over a minor portion of the bottom of the flanged base located approximately midway of the length of the rail, in combination with transverse ties arranged at intervals of the rail length, tie plates between the rail and the ties having spike holes and some of which plates contact the corrugations of the rail and have corresponding corrugations engaging with those of the rail, and spikes having body members which are driven through the holes in the tie plates into the ties, and heads which contact with the flanged base of the rail.

In testimony whereof I affix my signature.

HENRY J. COERPER.
